TOY BOAT CONSTRUCTION

Walter L. Ripley, Sharpsburg, Md., assignor to
Gladys A. Ripley, Sharpsburg, Md.

Application November 20, 1944, Serial No. 564,257

8 Claims. (Cl. 46—93)

The present invention relates to toy boat construction and has particular reference to a toy boat adapted for home assembly.

One object of the invention is to provide a toy boat which is designed for sale to the public in the form of a kit embodying a multiplicity of disconnected parts requiring a minimum of skill for assembly.

Another object of the invention is to provide a toy boat designed so that the disassembled parts are susceptible of compact arrangement within a relatively small container or kit.

A further object of the invention is to provide a novel toy boat having a multiplicity of parts capable of home assembly to form a floatable boat.

Still another object of the invention is to provide a toy boat designed for sale in knocked down kit form and having preshaped parts providing curved lines simulating the lines of a full size boat.

A still further object of the invention is the provision of a toy boat which is capable of manufacture for sale at a relatively low cost.

The above and various other objects of this invention will be apparent from the following description and appended claims when taken in conjunction with the accompanying drawings wherein:

Figure 1 is a side elevational view of a preferred form of the assembled boat;

Figure 2 is a top plan view of Figure 1;

Figure 3 is a longitudinal vertical section taken on line 3—3 of Figure 2;

Figure 4 is an exploded perspective view showing the hull parts in separated relation;

Figure 5 is a perspective view of the main deck board and a reinforcing piece therefor;

Figure 6 is an exploded perspective view of the cabin forming parts;

Figure 7 is a side elevational view of the rudder and propeller attachment;

Figure 8 is a top plan view of the disconnected parts arranged in kit form in a container.

Referring to the drawings wherein for the purpose of illustration the boat is shown as of the tug boat type, and in which like reference characters indicate like parts, 20 designates a pre-shaped piece formed from an elongated strip of sheet material, such as wood veneer, bent substantially U-shape to form the opposed longitudinal sides 22 and the bow portion 24 of a boat hull. The bow portion of this shell piece converges to a prow 26 of relatively small radius midway at the ends of the strip, which has a diminishing taper from the prow to the spaced apart stem ends.

At its aft end the boat is provided with an elongated stern block 28 of approximately rectangular cross section and preferably designed to provide flat top and bottom faces 30 and 32 and flat end faces 34 acutely angled with relation to the top face 30 in downwardly converging planes. The stern block 28 is designed for assembly in a transverse position between the aft end of the shell 20 with substantial portions of the shell sides 22 overlying and secured to the respective oblique end faces 34.

Within the bottom marginal portion of the shell strip 20 is fitted and secured a hull bottom member 36 such as a rigid board of plywood or the like having an edge contour conforming to the horizontal outline of the shell and extended under the block for securing against the bottom face 32 thereof. Bottom board 36 is mainly planar and may be entirely so, although in the present embodiment the forward portion has a slight upward curvature.

Within the upper portion of the hull shell 20 is fitted and secured a main deck member 38, shaped substantially in correspondence with the contour of the bottom, and having a slight downward slope toward the stem. This deck member advantageously comprises a board of stiff plywood. The aft end of the deck board 38 overlies and is secured to the top face 30 of the stern 28.

30 To the underside of the forward end of the deck member 38 is secured a flat substantially semi-circular toe piece 40 adapted to provide a reinforced connection with the prow of the shell. The deck forming board 38 is also provided, symmetrically of its longitudinal center line, with a relatively large cabin receiving opening 42.

40 A second pre-shaped member 44 comprising a strip of wood veneer or like sheet material bent in the form of a U is adapted for slidably sprung fitting in the deck opening 42 to form the side and forward walls of a cabin shell. The ends of this strip are cut down to provide relatively narrow coaming sections 46. At the forward end of the shell strip 44 is mounted an elongated

45 vertically disposed spar piece 50 secured to the cabin wall and notched to form a shoulder providing a horizontal face 52. On the top edge of the cabin shell 44 is secured a flat veneer sheet 54 forming a cabin top deck and having its marginal portion projecting outwardly of the walls. The forwardly extended portion of the top deck 54 overlies and is secured upon the spar face 52.

55 As shown at Figure 3, the bottom end of spar 50 abuts the main deck 38 to limit downward insertion of the shell strip. The aft end of the

top deck 54 terminates forwardly of the rear edge of deck opening 42 to provide a drop entrance passage for the cabin, the aft ends 46 of the cabin wall providing side coaming thereat. To the underside of the float deck piece 54 is connected a transversely extending bar 56 of wood or the like abutting the after parts of the elevated sides of the cabin shell in the nature of a deck beam.

To the stern end of the assembled boat is attached a rectangular frame 58 having apertured horizontal and vertical projections 60 and 62 adapted to be nailed to the stern block 28 and to the stern end of the bottom 36. This frame carries a rearwardly extended rudder web 64 and a propeller or propeller simulating element 66.

The component parts of the hull and cabin structure are preferably connected by adhesive or nails or both forming a part of the kit as indicated at 67. Thus, the stern end portions of the bottom and the main deck members, overlapping the lower and upper faces respectively of the block 28, may be secured in face to face relation therewith by adhesive and may be reinforced, particularly the deck board, by nails 68. Likewise the securement of the bottom 36 within the lower margin of the shell strip 20 may be effected by adhesive with nails 70 and, if so desired, a sealing strip 72 may be disposed to cover this joint to assure water tight connection. The edges of the main deck board 36 are advantageously connected within the shell 20 by adhesive, the toe piece 40 providing an enlarged end area for securely attaching the toe end of the deck to the prow of the shell and receiving a positioning nail 73, if desired. The upstanding spar 50 is connected to the forward part of the cabin shell 44 by nails 74 while the forward part of the roof deck 54 is secured upon the shoulder face of the spar by a nail, as indicated at 76. The deck 54 may be fastened on the top edge of the cabin shell by adhesive connection therewith and through adhesive connection of the ends of the beam 56 with the cabin walls.

Thus, the present invention provides a toy boat construction which is sold to the purchaser in kit form, including a multiplicity of disconnected parts of novel structure and relationship as shown in Figures 4 to 8 and which are susceptible of assembly by a person having relatively little skill in the art, for instance, a small boy. The operation of assembling the constituent parts is both interesting and instructive and the resulting boat structure is quite durable, although the parts thereof may be manufactured at a relatively low cost.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A toy boat comprising a hull having a deck provided with an opening; a unitary strip of sheet material, bent to form the sides and forward wall of a cabin, said strip having its lower portion slidably fitted into and frictionally held in the opening of the deck; and a cabin top form-

ing deck member secured on the upper edge of the said strip.

2. A toy boat comprising the hull, a deck member extending longitudinally of the hull and provided with an opening, a strip of sheet material bent to approximately U-shaped form frictionally fitted within the deck opening to form the sides and forward wall of a cabin, and a flat sheet secured in cabin top forming arrangement upon the upper edge portion of said strip.

3. In a toy boat, a hull shell member comprising an elongated strip of sheet material bent to approximately U-shaped form to provide the side walls and the converging bow of a boat, a block disposed transversely between and secured to the stern ends of the shell forming strip, a bottom forming board secured to the lower edge portion of the shell and to the underside of said block, and a substantially flat deck forming board secured within the upper part of the shell and having its stern end secured on the top of said block.

4. In a toy boat, a hull shell member comprising an elongated strip of sheet material bent in approximately U-shaped form to form the side walls and the bow of a boat, an elongated block disposed transversely between and secured to the stern ends of the shell forming strip, a bottom board secured to the lower edge portion of the shell and to the underside of said block, a substantially flat deck board secured within the upper part of the shell and having its stern end secured on the top of said block, the said deck board having an opening therein, a cabin shell comprising a strip of sheet material bent to form the side and front walls of a cabin and fitted within the deck opening, and a flat sheet secured upon the upper edge of the cabin shell to form a covering deck therefor.

5. A toy boat as defined in claim 4 wherein a spar member is secured in vertically disposed position to the forward end of the cabin shell for abutment with the deck to limit the downward insertion of the cabin strip within the deck opening.

6. In a toy boat, a hull shell comprising an elongated strip of veneer pre-shaped to form the sides and forwardly converging bow portion of a boat, an elongated block having flat top, bottom and end faces mounted transversely between the separated stern ends of the hull shell and having its end faces secured to said shell ends, an approximately flat bottom board fitted within and secured to the lower marginal portion of the shell and having its stern end portion secured against the bottom face of the block, and a flat deck board secured within the upper portion of the shell substantially parallel with the bottom and having its stern end portion overlying and secured to the top face of said block.

7. In a toy boat, a hull shell comprising an elongated strip of veneer pre-shaped to form the sides and forwardly converging bow portion of a boat; an elongated block having flat top, bottom and end faces mounted transversely between the separated stern ends of the hull shell and having its end faces secured to said shell ends; an approximately flat bottom board fitted within and secured to the lower marginal portion of the shell and having its stern end portion secured against the bottom face of the block; a deck board secured within the upper portion of the shell substantially parallel with the bottom and having its stern end portion overlying and secured to the top face of said block, the said deck board having a relatively large opening symmetri-

cally of its longitudinal center line; a cabin shell comprising a strip of wood veneer pre-shaped to an approximately U-shaped form and slidably fitted within the deck opening to form the sides and forward wall of a cabin; an upstanding spar secured to the forward portion of the cabin shell and adapted to abut the top of the deck board to limit the downward insertion of the cabin shell; and a flat deck wood veneer secured on the top edge of the cabin shell.

8. A boat construction kit comprising a pre-shaped sheet of material for forming an open stern hull shell; a substantially flat bottom board pre-shaped to fit within and be secured to the lower edge of said shell; a spacer block adapted to fit between and be secured to the stern ends

5 of said shell and to rest on and be secured to the stern marginal surface of said bottom board; a preformed substantially flat deck board having a cabin opening therein and adapted to fit within said shell and be secured thereto in spaced relation to said bottom board with its stern marginal surface overlying and secured to the upper surface of said spacer block; a pre-shaped sheet of material for forming an open stern cabin shell 10 and adapted to be sprung fitted into said cabin opening; a spar adapted to be secured to said cabin shell and limit the extent of insertion of said cabin shell into said cabin opening; and a substantially flat deck cover for covering said 15 cabin shell.
